(57) CLAIM

I claim the ornamental design for a support for cigars and the like on a golf cart, as shown and described.

DESCRIPTION

FIG. 1 is a perspective view from the left side of the preferred embodiment of the support for cigars and the like on a golf cart of the present invention;

FIG. 2 is a perspective view from the right side of the embodiment shown in FIG. 1;

FIG. 3 is a front view of the embodiment shown in FIG. 1;

FIG. 4 is a side view, with the opposite side view being identical, of the embodiment shown in FIG. 1;

FIG. 5 is a top view of the embodiment shown in FIG. 1; and,

FIG. 6 is a bottom view of the embodiment shown in FIG. 1.
